MACHINE FRAME

Frederick A. Prahl, Jr., Wenham, Mass., assignor
to United Shoe Machinery Corporation, Flem-
ington, N. J., a corporation of New Jersey

Application July 25, 1945, Serial No. 606,895

3 Claims. (Cl. 248—121)

1

This invention relates to machine frames and is herein disclosed, by way of example, as embodied in a frame suitable for use in many types of shoe machinery.

It has hitherto been customary in the building of machines to support the operating head by a rigid cast metal column having an integral base adapted to rest upon the floor. Such structures, however, often required an excessive quantity of metal and were unnecessarily heavy. Because of the weight and irregular contour of such structures they were difficult to move, it being customary to provide pinch bar recesses in the base close to the floor so that the machine could be inched along the floor to the proper position or could be raised upon a truck conveniently. In many instances, however, breakage of the legs or floor engaging lugs of such machines occurred from careless handling during transportation. Breakage of the legs in some instances caused the machine to fall, subjecting those moving the machine to danger of serious injury. Moreover, in machines having a heightwise adjustable head, such metal frames were unsightly by reason of their failure to provide any housing for the adjustable members which directly supported the head.

It is an object of the present invention to provide a heightwise adjustable machine frame which is relatively light, inexpensive, and neat looking. In an illustrative machine frame embodying the invention and disclosed herein, the column portion of the frame is formed of sheet metal. The machine head is carried by a post which is slidably mounted, for heightwise adjustment, in a bearing sleeve secured to the upper portion of the column. Whether adjustable for height or not the present embodiment of the invention is such that much weight is eliminated in the machine frame and the column structure constitutes a shock absorbing connection secured between a rigid cast metal base and a cast metal machine supporting member. For this purpose the column is formed from a single inexpensive thin rectangular plate of relatively resilient metal sheet bent into an open box-like structure of C-shaped cross-section with substantial vacant space inside, the opening between the edges of which bent sheet extends heightwise from the machine supporting member to the base member to provide a torsional yielding action about an axis running lengthwise of the column when stress is applied between said members. Accordingly, to enable the torsional action of the column to be accommodated, the column is fixed to

the flanges of a pair of flanged end plates secured to the supporting and base members by fastenings spaced inwardly from the flanges on the plates. The plates provide effective resilient flexure between the flanges and the fastenings in a direction at right angles to the planes of the plates.

By constructing the column in this way it is made large enough to insure space within it for essential auxiliary devices for the machine such as a height-adjusting supporting post, clamping means therefor, a treadle rod and other similar adjuncts. With ample space within the column there is no necessity for the use of external appendages so that the appearance will not be affected adversely, the general contour of the frame being unbroken while enabling easy handling of the machine without subjecting those moving it from place to place to injurious contact with irregular or pointed projections thereon. Vibratory effects of the parts within the column one against another also will largely be avoided.

As illustrated, the height adjusting post is slidably mounted within a vertical clamping sleeve at the upper end of the column.

These and other features of the invention, including certain details of construction and combinations of parts, will be set forth in connection with an illustrative machine and will be pointed out in the appended claims.

Referring now to the accompanying drawing, Fig. 1 is an angular view of a machine frame embodying the invention;

Fig. 2 is a sectional view in side elevation of the frame shown in Fig. 1;

Fig. 3 is a section taken on the line III—III of Fig. 2, the housing being omitted;

Fig. 4 is a fragmentary section taken on the line IV—IV of Fig. 2;

Fig. 5 is a section taken on the line V—V of Fig. 2; and

Fig. 6 is a sectional view taken along the line VI—VI of Fig. 2 showing the supporting column only.

The improved machine frame disclosed herein comprises a hollow vertical column 10 of relatively flexible sheet metal mounted upon a cast metal base 12 and indirectly carrying a cast metal plate 14 upon which may be mounted a machine head 16, indicated by broken lines in the drawing. This frame is suitable for supporting many different types of machine head, the one shown herein by way of example being the head of a platform cover lasting machine

disclosed in United States Letters Patent No. 2,411,827, granted November 26, 1946, upon the application of Joseph Fossa.

The column 10 is a box-like structure, of substantially rectangular C-shaped cross-section, composed of a single piece of sheet metal bent to form three closed sides with spaced edges at the rear of the column and the bottom and top edge secured to the base 12 and mounting plate 14, respectively. The rear side of the column is not completely closed, but is formed with a heightwise opening extending the full length of the column. The edges of the sheet metal adjacent to said heightwise opening are turned inwardly to form stiffening flanges 18 (Figs. 2 and 5). A lower end plate 20 has three upturned flanges 22 which are fixed by welding to the front and side walls of the column 10. The column 10 is secured upon the base 12 by fastening screws 24 passing through the plate 20 and the top wall of the base 12 at positions spaced inwardly from the flanges of the plate. The upper end of the column 10 has secured thereto an end plate 26 similar in all respects to the end plate 20. Depending from the plate 26 is a vertically arranged machine supporting bearing sleeve 28 having a radial flange 30. Fastening screws 32 passing through the plate 26 at positions spaced inwardly from the flanges of plate 26 and threaded into the flange 30 secure the bearing sleeve 28 to the plate 26. Slidably mounted for heightwise adjustment in the bearing sleeve 28 is a relatively rigid cylindrical hollow post 34 having an outwardly extending flange 36 at its upper end. The post is substantially smaller in diameter than the width and the front to rear depth of the column to provide a vacant space at all sides of the post within the column. Secured upon the flange 36 by screws 38 is the head-supporting plate 14. It will be observed that the plate 26 has a central opening to accommodate the post 34. As a matter of convenience in manufacture, the lower plate 20 is made with a similar central opening. The post 34 has a heightwise extending slot 40 through which extend a pair of post securing carriage bolts 42. The square portions of the shanks of the bolts 42 slidably engage the slot 40 without turning therein. The bolts continue through openings in the sleeve 28 and are secured by nuts 44 which clamp the post 34 in any desired position of heightwise adjustment.

As has been stated, the column acts as a shock absorbing connection between the base and the machine supporting member comprising the bearing sleeve 28. This action is the result of two features in the construction, first the spacing of the fastening screws 24 and 32 from the flanges of the respective plates which they secure and, second the heightwise opening between the edges of the column plate. Yielding torsional action in the column is permitted because the plates 20 and 26 flex slightly toward and away from the base 12 or flange 30 of the machine supporting sleeve 28, the vertical edges of the column plate moving slightly relatively to each other.

In telescopic relation to the column 10 and serving as a housing for the portion of the post 34 which extends above the column is a frame member 46 of sheet metal having an upper end plate 48 which is secured by screws to the under surface of the flange 36. The frame member 46, like the column 10, is substantially rectangular in cross section with its rear side not completely

closed, thereby providing access to the nuts 44. The end plate 48 has three flanges 50 which are similar to the flanges 22 of the end plate 20 and which are welded to the inner surface of the wall of the frame member 46 to support the frame member in depending relation to the flange 36. Because of the telescoping engagement of the frame member 46 with the column 10 the head 16 may be adjusted to any desired height without altering the appearance of the machine frame, the effect of the extension of the post 34 thus being to render the column 10 apparently extensible and collapsible heightwise as the head is adjusted up and down. Furthermore, the clamping nuts are accessible from between the flanged vertical edges of the sheet metal column and are disposed well inside the column to eliminate external appendages outside the column, thus presenting a pleasing appearance and a smooth unbroken external contour while providing adequate accessibility.

The mechanism of the machine may be controlled by a treadle 52 fulcrumed in the base 12 and connected to the lower end of a treadle rod 54 (Fig. 2). An extension rod 56 is clamped to the rod 54 by a clamping block 58 which provides for relative heightwise adjustment of the rod 56 with respect to the rod 54. The upper end of the rod 56 is pivotally connected to a lever 60 (see also Fig. 3) which is bow-shaped to clear the post 34 and which is fulcrumed upon a pin 62 carried by a bracket 64 which is dependently secured to the flange 36. Both the control lever 60 and the pin mounting bracket 64 are disposed within the outlines of the upwardly projected external contour of the sheet metal column 10 inside the enclosing frame member 46. One end only of the pin 62 extends beyond the projected external contour of the column. Extending from that end 40 of the pin 62 outside the enclosing frame member 46 is a crank arm 66 which is pivotally connected to a rod 68 which, in turn, is connected to the mechanism to be controlled.

The machine is driven from a motor 70 by a belt 72 running over a pulley 74 mounted on the head 16. To accommodate heightwise adjustment of the head 16 and also to enable the tension of the belt 72 to be adjusted or belts of various lengths to be employed, the motor 70 is carried upon a bracket 76 with provision for heightwise adjustment on the column 10. To this end, the bracket 76 is mounted upon a clamping plate 78 which bridges the opening in the rear wall of the column 10 and which bears against the outer surface of the rear wall adjacent to the opening. Within the column 10 and bridging the opening are a pair of clamping bars 80 and 82. Each of these bars engages the edges of the turned flanges 18. Threaded into each of the bars 80, 82 and passing through the clamping plate 78 are clamping screws 84 which, when tightened, exert a clamping pressure through the adjacent flange 18. There are thus four clamping screws 84 distributed adjacent to the corners of the plate 78, two of them being threaded into the upper clamping bar 80 and the other two into the lower clamping bar 82. There is only slight clearance between the shanks of the screws 84 and the adjacent sides of the flanges 18, so that the flanges serve as a guide to determine the lateral position of the motor 70 and thereby keep the motor pulley in alignment with the pulley 74. While the clamping pressure of the screws 84 is sufficient to prevent displacement of the motor bracket 76 vertically and tends to stiffen the column some-

what against torsion; the pressure of the screws exerts a frictional effect only along edges of the column to reduce yielding action but not to prevent it.

For general utility and convenience in many types of machines a shelf 86 is mounted upon the column 10. This shelf is formed of sheet metal and has a stiffening flange 88 extending downwardly from its outer edge and a flange 90 extending downwardly from its inner edge, that is, the edge adjacent to the frame member 46. The shelf 86 is supported by a pair of screws 92 and 93 which are threaded one above the other into a block 94 welded to the inner surface of the column 10. The flange 90 is spaced from the column 10 by a pair of spacer sleeves 96 which surround the screws 92 and 93 and which are interposed between the flange 90 and the column 10. The frame member 46 has a vertical slot 98 (Fig. 1) which provides clearance for the sleeves 96 and thus leaves the frame member free for heightwise adjustment. The shelf 86 is reinforced at the locality of its attachment to the column 10 by a piece of sheet metal 100 welded to the depending flange 90 and having end portions 102 bent diagonally forward to form stiffening webs which extend to the corners of the shelf. The upper portions of the webs 102 are flanged over for attachment to the under surface of the shelf. As shown in Figs. 1 and 4, the shelf 86 is notched to partially embrace the two sides of the machine frame. In order to provide additional support to the laterally extending portions of the shelf, a flanged bracket 104 is secured by bolts 106 to the depending flange 88 on each side. Each bracket 104 is, in turn, secured to the frame member 46 by a carriage bolt 108 the head of which extends into a slot formed by two parallel flanged strips of sheet metal 110 welded to the outer surface of the frame member 46. When the machine head is to be adjusted for height, the bolts 108 are first loosened to set the frame member 46 free for such adjustment.

A switch box 112 is mounted upon the column 10 by the screw 93 and a similar screw 114 threaded into a block 116 welded to the inner surface of the column 10. Surrounding the screw 112 is a spacing sleeve 118. The heads of the screws 93 and 114 are received between a pair of flanged metal strips 120 resembling the strips 110 and screwed to the rear wall of the switch box 112. The strips 120 are clamped in position by the screws 93 and 114 before the switch box is secured to the strips.

It is evident that the machine frame described above is lighter, cheaper and more resilient than a cast metal frame wherein the column and the base are integral. The above-described frame, moreover, can be disassembled and the various portions packed separately for convenience in shipping. Even when the frame is not disassembled for shipping the torsional yielding action of the column protects the machine and the operating parts supported by the column from possibility of injury as a result of vibration, impact or rough handling. The construction described is particularly advantageous when the machine is being moved along a hard cement floor by a pinch bar, inserted in recesses for this purpose, one of which recesses is indicated at 122 in the base 12. The yielding torsional action of the column greatly assists in reducing breakage when a pinch bar is employed. It is so constructed as to hold the machine head 16 against turning, not only during the operation of the machine, but even

during the heightwise adjustment of the head. Such turning, in the absence of some provision to the contrary, would be practically unavoidable during heightwise adjustment. Any change from the accustomed position of orientation of the head, if permitted, would cause inconvenience to the operator. Turning of the head, furthermore, would interfere with the operation of the mechanism controlled by the treadle 52 and might interfere with the heightwise adjustment of the head and even cause the rectangular telescoping frame member 46 to warp out of shape by jamming it against the rectangular column 10, with possible damage to the surface finish of the column. In the frame disclosed herein, turning of the machine head during the operation of the machine is prevented primarily by the clamping action of the carriage bolts 42. During heightwise adjustment of the head, such turning is prevented by the engagement of the shanks of the bolts 42 with the slot 40.

Having described my invention, what I claim as new and desire to secure by Letters Patent of the United States is:

- 25 1. A fabricated frame for a machine of the type described having rigid, cast metal, machine supporting and base members, in combination with a shock absorbing connection between said members comprising a hollow vertical column formed from a single rectangular plate of relatively resilient sheet metal bent into an open box-like structure of C-shaped cross section with closed front and side walls and substantial vacant space inside, the fourth side of the column being partly closed but with a heightwise opening and flanged end plates, having their flanges fixed to the front and side walls of the column and being secured to the machine supporting and base members by fastenings spaced inwardly from the flanges thereon to accommodate torsional action in the column through flexure of the plates between the flanges and the fastenings at right angles to the planes of the plates.
- 30 2. A fabricated frame for a machine of the type described having a rigid cast metal base member, in combination with a shock absorbing hollow vertical column of relatively resilient sheet metal bent into an open box-like structure with substantial vacant space inside and with spaced edges at the rear, a radially flanged bearing sleeve secured to the upper edge of the column, a rigid hollow cylindrical post within the bearing sleeve projecting into the column of sufficiently small diameter to provide space at all sides of the post within the column, and means accessible from between the vertical edges of the sheet metal column but disposed inside the column for adjustably clamping the post to the sleeve without external appendages outside the column.
- 35 3. A fabricated frame for a machine of the type described having a rigid cast metal base member, in combination with a shock absorbing hollow vertical column of relatively resilient sheet metal bent into an open box-like structure with substantial vacant space inside and with spaced edges at the rear, a radially flanged bearing sleeve secured to the upper edge of the column, a rigid hollow cylindrical post within the bearing sleeve projecting into the column of sufficiently small diameter to provide space at all sides of the post within the column, means accessible from between the vertical edges of the sheet metal column but disposed inside the col-

umn for adjustably clamping the post to the sleeve without external appendages outside the column, a bow-shaped machine control lever disposed at the upper end of the post in surrounding relation thereto within the upwardly projected external contour of the column, a bearing block within the upwardly projected contour of the column supported by the post, a rotary pin in the bearing block to which the control lever is secured, and a treadle rod connected at its upper end to the lever and extending downwardly through the free space between the column and the cylindrical post.
